THREAD ROLLING APPARATUS

Victor Hill Fray, Auckland, New Zealand

Application March 1, 1950, Serial No. 147,066

5 Claims. (Cl. 80—7)

1

This invention relates to thread rolling apparatus whereby screw threads are formed by a rolling process on blanks of metal thread screws, bolts and the like, the objects of the present invention being the provision of improved thread rolling apparatus which will very appreciably speed up the forming of the rolled threads on the blanks.

At present, the threads are formed or rolled on the blanks between flat plates which have forming threads cut in their adjacent faces, one plate being stationary while the other is moved reciprocally above the other, one blank at a time passing between these plates so that for one stroke of the movable plate one blank has the thread rolled thereon, the movable plate having to then return to starting position before the next blank is admitted for the rolling of the thread thereon.

While the flat plate reciprocally operated type of thread rolling apparatus is that which is in general use, I am aware that rotary roller type thread rolling apparatus is known, but that it has not come into general use even though devised many years ago, because of not being positive and consistent enough in its action, this known roller type of apparatus rolling the thread on one blank at a time.

It is well known that in most forms of apparatus, greater speeds of operation are obtainable when the movement is rotary as against reciprocating and therefore my invention has been devised for the purpose of speeding up production in the thread rolling operation by the provision of improvements in the rotary type of apparatus which will enable several blanks to be progressively roll threaded in the machine at the one time.

Broadly the invention comprises improvements in thread rolling apparatus of the type in which the threaded periphery of a rotatable thread roller is disposed adjacent to the threaded curved face of a stationary segment with a gap between the roller periphery and the threaded curved face through which the blanks pass, wherein means are provided for feeding the blanks into such gap which are capable of being advanced or retarded while the machine is in operation in order that such blanks be entered to the gap inlet at the instant when a thread start of the roller is in correct register with a thread start of the segment.

In describing the invention, reference will be made to the accompanying drawings in which:

Figure 1 shows an elevation of the improved thread roller apparatus,

2

Figure 2 is a plan view of Fig. 1 with part of the upper bearing broken away to show the thread roller and segment below same,

Figure 3 is a side elevation of Fig. 1.

5 Figure 4 is an enlarged sectional elevation of the blank feed timing mechanism,

Figure 5 is a plan view of the bosses with pins,

Figure 6 is a cross section of the spindle extension, and

10 Figure 7 is a side elevation of the mechanism to show the spiral slots in the sleeve and the engagement of the boss pins therewith.

In the invention, the known apparatus comprises a vertical spindle 1 with the thread roller 2 rigidly secured thereto and mounted in bearings 3 and 4 which extend from the vertical upwardly extending portion 5 of a main frame or head portion 6 which is rigidly secured to a base plate or the like 7, provision being made as by 15 gearing or the like (not shown) for drive of this spindle 1 and the roller 2 secured thereon, portion of the periphery of the roller 2 being disposed closely adjacent to the curved face of a stationary segment 8 which is adjustably and 20 slightly eccentrically mounted to the vertical portion 5 of the main frame 6 to leave a gap 9 (see Fig. 2) between the roller 2 and the segment 8, the curved face 8a of the segment 8 being provided with the forming threads which are 25 complementary to the forming threads in the periphery of the thread roller 2, means being provided to enter the blanks to the gap inlet 9a or feed-in end of the gap 9.

To such known apparatus the improvements of 30 the present invention are applied and the improved mechanism is such as to enable several blanks 10 to be in the machine at the one time, progressively having the rolled threads applied thereto.

35 40 This is made possible because of the forming threads in the thread roller 2 having positions at the edge which are called thread starts and thus a thread roller for say one eighth inch screws may have as many as 32 starts, this number of starts becoming less in respect of larger diametered screws having less threads per inch.

Accordingly, that portion of the periphery of the thread roller 2 which is disposed adjacent to the stationary segment 8 may have say 6 starts 45 and it would therefore be possible to have 6 blanks passing along the gap 9 at the one time with a supply of the blanks 10 fed into the gap 9 in a continuous stream from hopper-feed apparatus (not shown) with mechanism feeding the 50 blanks 10 into the gap at the correct time for

register of a start of the roller 2 with the start of the segment 8.

Now this obtaining of correct register is of extreme importance in that even a minute inaccuracy results in the rolled thread being of incorrect form, it having been found that even a change of revolutions from moderate to high can result in a time lag in operation of the mechanism which will result in the rolled thread being defective.

To obtain this accuracy by an original setting of the machine has been found to be unsatisfactory and therefore mechanism has been devised so that while the machine is running at its working speed under working conditions, adjustments can be effected and at any time when inaccuracy occurs, it can be immediately remedied with the machine continuing to operate.

The roller spindle 1 is provided with an extension 1a of smaller diameter extending up from its top end, such spindle extension 1a being diametrically split substantially from top to bottom and also having a bore 11 extending from substantially top to bottom thereof so that in effect there are two oppositely disposed slots 12 and 12a along the length of the spindle extension 1a opening into the bore 11 therein (see Fig. 6).

The top end of this spindle extension 1a has a short thread 13 (see Fig. 4) with a nut 14 screwed on to same so that the split portions cannot spread outwardly, inward spring being prevented by a short bush 15 secured in the end of the spindle bore 11, a bore 15a in such bush slidably receiving an operating spindle 16 which extends down within the bore 11 and also extends to above the top of the spindle extension 1a to have a spool or the like 17 secured at its top end.

Rotatably and neatly fitting over the spindle extension 1a between its bottom end and the nut 14 at the top thereof there is a sleeve 18 and secured to the bottom end of such sleeve 18 there is an indexing ratchet wheel 19, the sleeve 18 having two slots 20 and 20a cut therein (see Fig. 7) at opposite sides thereof which slots 20 and 20a are of long spiral form, being at only a slight angle in relation to the axis of the sleeve 18.

The operating spindle 16 passing down within the bore 11 in the spindle extension 1a is slightly reduced in diameter 16a at its lower portion and on such lower reduced portion 16a two bosses 21 and 21a are slidable between the upper shoulder 16b as presented by the reduction in diameter and two locking nuts 22 on a thread 16c at the extreme bottom end of the spindle reduction 16a, a compression spring 23 on the spindle being disposed between these bosses 21 and 21a and tending to keep them bearing against the shoulder 16b and the nuts 22 respectively.

These two bosses 21 and 21a (see Fig. 5) each have two pins 21b extending therefrom diametrically opposite and such pins 21b extend through the slots 12 and 12a in the roller spindle extension 1a (see Fig. 4) into the spiral slots 20 and 20a in the sleeve 18 and while the roller spindle slots 12 and 12a are just wide enough to permit passage of the pins 21b, the spiral slots 20 and 20a are appreciably wider, with the result that one pin 21b in a slot 20 or 20a bears against one side thereof while the other pin 21b bears against the other side of the same slot, the action of the compression spring 23 being to cause these pins 21b to apply some pressure against their respective sides of the spiral slots 20 and 20a.

In effect therefore, these pairs of pins 21b pro-

jecting into the opposite spiral slots 20 and 20a of the sleeve 18 are acting as keys whereby drive of the roller spindle extension 1a is imparted to the sleeve 18 and the ratchet wheel 19 mounted thereon, but as these pins 21b can be moved up or down the spindle extension 1a by these movements being imparted to the spool 17, any such movements of the pins 21b because of being engaged in the spiral slots 20 and 20a will cause 10 advancing or retarding movements of the sleeve 18 and the ratchet wheel 19 in relation to the roller spindle 1.

The spool 17 at the top end of the operating spindle 16 is engaged by the forked end 24a of 15 an operating arm 24, the other end of this arm having a boss 24b which is vertically slidable within a tubular screw housing 25 which is secured to extend vertically up from the main frame 6, this screw housing 25 having a screw 26 which is rotatable therein by the turning of 20 a handwheel 27 secured at the top projecting end thereof, the screw 26 screwing through a threaded bore in the boss 24b, there being a slot 28 in the housing 25 through which this arm 24 25 passes from its boss 24b.

The indexing ratchet wheel 19 may have (if so desired) the same number of teeth therein as the number of thread starts of the thread roller 2, or may have half this number of starts, 30 and disposed to engage this ratchet wheel 19 where is a pawl 29 mounted on the upper end of a pecker spindle 30, such vertical pecker spindle being supported in a bearing block 31 which is secured to the main frame 6 and at its bottom end has a lever arm 32 secured thereto (see Fig. 2) to the end of which a connecting rod 33 is 35 pivotally connected, this connecting rod 33 being adjustable as to length and being connected to the pecker 34, such pecker 34 being in the form of a narrow blade disposed vertically on edge and being slidable through a guide block 35 so as to project its free end towards the feed-in end 9a of the gap 9 between the roller 2 and the segment 8, a strong spring 36 such as of wound type as shown in Fig. 1 being engaged between 40 the bearing block 31 and the lever arm 32 and tending to hold the pawl 29 hard in engagement with the ratchet wheel 19.

A blank feeding chute 37 from the hopper-feed apparatus (not shown) brings the blanks 50 10 with their heads all uppermost to a position at the inlet end 9a of the gap 9, the movements of the pawl 29 as caused by the rotation of the ratchet wheel 19 and the spring 36 causing the pecker 34 to push the blanks 10 from the end 55 of the chute 37 into the gap 9 one at a time at the correct instant when the register of a start of the roller 2 with a thread formation of the segment 8 takes place.

In use or operation, with the ratchet wheel 19 60 having the same number of teeth as the number of thread starts in the thread roller 2, the pecker 34 will be moved to push a blank 10 into the gap 9 every time a thread start of the roller 2 is in correct register with the thread formation 65 at the leading end of the stationary segment 8 at the gap inlet end 9a and therefore with a thread roller 2 having 32 starts and a ratchet wheel 32 teeth, 32 blanks 10 will pass through the gap 9 per revolution of the roller 2, although 70 it will be understood that of this number there may be only say six blanks 10 within the gap 9 at any time, this being determined by what proportion of a circle the stationary segment 8 represents.

Accordingly, the blanks 10 are rolled from end to end of the gap 9 and as the stationary segment 8 is eccentrically mounted so that the gap 9 becomes narrower towards the discharge end thereof, the threads are gradually roll formed to the finished true shape.

If however there is not absolutely correctly timed entry of the blank 10 to the gap 9 at the time when there is register of a start on the roller 2 with a start on the segment 8, it will be understood that the threads formed at opposite sides of the blank 10 by the roller 2 and the segment 8 are not in agreement or register, and thus the one will build up a thread to be flattened or otherwise deformed by the other and when applying fine threads such as 40 per inch, a very small inaccuracy in the register results in the blanks being damaged and thus rendered useless.

With the blanks passing through the machine at high speed, any fault in register can soon result in many gross of the blanks being wasted, but with such small articles, it is important to keep the machine running and prevent stoppages for adjustments and this is the great benefit of the present invented apparatus.

If the machine gets out of true adjustment as in fact does occur for reasons difficult to locate and remedy, the handwheel 27 is turned so that the screw 26 is rotated to cause the operating arm 24 to be moved up or down as may be required in order to advance or retard the ratchet wheel 19 in relation to the thread roller 2, such advancing and retarding being determined by close inspection of the thread of a blank which has just passed through the machine.

Such movement of the operating arm 24 transmitted to the spool 17 causes the operating spindle 16 to be raised or lowered as the case may be within the bore 11 of the spindle extension 12 and therefore presuming that it has moved down, this will cause its shoulder 16b to push down the upper boss 21 with its pins 21b, such movement causing the compression spring 23 to be compressed to a further extent and causing a small movement, or slack to be obtained between the engaging pins 21b of the boss 21 and their respective engaged sides of the spiral slots 20 and 20a in the sleeve 18 and then the movement being downward, the spring 23 pushes the lower boss 21a downward with the result that the pins 21b of the respective bosses 21 and 21a again spread apart to their original distances, thereby again bearing at their respective engaging sides of the spiral slots 20 and 20a.

Now this has had the effect of bringing the pins to bear in the spiral slots 20 and 20a at a slightly lower level and therefore, this has resulted in the sleeve 18 and its attached ratchet wheel 19 having been advanced slightly in position, this causing the pawl 29 to engage the bottoms of the teeth slightly earlier so that the pecker 34 pushes the blanks 10 into the slot or gap 9 that fraction of time advanced from previously which obtains the required register.

Upward travel of the operating spindle 16 will result in retarding movement of the ratchet wheel 19 and pecker 34, the lower boss 21a and its pins being first to move in this case as being pulled upward by the locked nuts 22 and through the compression spring 23 pushing the upper boss 21 and its pins upward to again come to bear.

It has been found that with the machine driven by an electric motor having an ammeter on the power line, the load as indicated by such ammeter is lowest when there is correct register and in

fact the obtaining of correct register can be obtained by effecting the adjustments while noting the reading of the meter.

This therefore permits of the introduction of known electric alarm apparatus, the alarm bell or like being operated when the load exceeds the meter reading which indicates proper operation of the machine, or the introduction of known electric overload release apparatus which would switch off the motor to stop the machine or to stop the feed of blanks to the machine when same is unattended and a fault occurs.

I claim:

1. A thread rolling apparatus of the type in which a thread roller connected to a rotatable spindle has the threaded periphery of the roller provided with a plurality of thread starts disposed adjacent to the threaded curved face of a stationary segment also having a plurality of thread starts so that there is a gap between the roller periphery and the threaded curved face of the segment in which gap a plurality of thread starts on the roller are simultaneously adjacent to the segment and to which gap the blanks to be provided with threads are fed by a movable pecker member, the improvement which comprises an interconnecting of said movable pecker member with said rotatable spindle for moving the former in timed relationship with the latter including an extension to the roller spindle, opposite slots formed in such roller spindle extension and a bore extending down into said spindle extension, a short bush secured in the top of such bore and a nut at the top of the spindle extension, an operating spindle slidable through the bush to extend down within the bore and to above the spindle extension with spool means secured at the top of such operating spindle, a sleeve rotatable over the spindle extension with an indexing ratchet wheel secured thereto and opposite slots of long spiral form cut in said sleeve, two bosses slidable within the spindle extension bore and over the lower portion of the operating spindle disposed within the latter, a shoulder to the operating spindle against which the upper boss bears and nuts at the bottom end of the operating spindle against which the lower boss bears, a compression spring between the bosses on the operating spindle and two pins extending from opposite sides of these two bosses passing through the slots formed in the roller spindle extension and moved into the spiral slots of the sleeve, a rotatably mounted pecker spindle, a pawl engaging the indexing ratchet wheel and mounted on the pecker spindle, a lever arm secured to the pecker spindle, a connecting rod effecting a connection between the lever arm and the movable pecker member, a guide block for such pecker member for guiding the free end thereof towards the feed-in end of the gap between the thread roller and the threaded segment, spring means for holding the pawl hard in engagement with the indexing ratchet wheel, and means for effecting raising and lowering of the operating spindle to thereby advance or retard the action of said pecker member while the thread roller is rotating.

2. A thread rolling apparatus as claimed in claim 1 wherein the means for effecting the raising and lowering of the operating spindle comprise an operating arm one end of which engages the spool at the top of the operating spindle while the other end has a boss which is slidable within a rigidly mounted tubular screw housing in which a screw is rotatable but not

slidable, such screw being threaded to screw through the boss end of the operating arm.

3. A thread rolling apparatus comprising a vertical spindle with a thread roller rigidly secured thereto and mounted in bearings extending from the upwardly extending portion of a main frame or head which is secured to a baseplate, a stationary segment mounted to the main frame and having a threaded curved face disposed eccentrically in relation to the thread roller with a gap between the threaded curved face and the adjacent portion of the roller, an extension to the roller spindle, opposite slots formed in such roller spindle extension and a bore extending down into said spindle extension, a short bush secured in the top of such bore and a nut at the top of the spindle extension, an operating spindle slidable through the bush to extend down within the bore and to above the spindle extension with spool means secured at the top of such operating spindle, a sleeve rotatable over the spindle extension with an indexing ratchet wheel secured thereto and opposite slots of long spiral form cut in said sleeve, two bosses slidable within the spindle extension bore and over the lower portion of the operating spindle disposed within the latter, a shoulder to the operating spindle against which the upper boss bears and nuts at the bottom end of the operating spindle against which the lower boss bears, a compression spring between the bosses on the operating spindle and two pins extending from opposite sides of these two bosses passing through the slots formed in the roller spindle extension and into the spiral slots of the sleeve, a rotatably mounted pecker spindle, a pawl engaging the indexing ratchet wheel and mounted on the pecker spindle, a lever arm secured to the pecker spindle with a connecting rod effecting a connection between the lever arm and a pecker member, a guide block for such pecker member for guiding the free end thereof towards the feed-in of the gap between the thread rollers and the threaded segment, spring means for holding the pawl hard in engagement with the indexing ratchet wheel, and means for effecting raising and lowering of the operating spindle comprising an operating arm one end of which engages the spool at the top of the operating spindle while the other end has a boss which is slidable within a rigidly mounted tubular screw housing in which a screw is rotatable but not slidable, such screw being threaded to screw through the boss end of the operating arm.

4. A thread rolling apparatus comprising a frame, a continuously threaded cylindrical roller die having a plurality of threaded starts, means for rotatably supporting said roller die in said frame, a cooperating stationary die having an arcuate concave face having a plurality of thread starts, means for fixedly connecting said stationary die to said frame with said arcuate face disposed adjacent to said roller die with a gap therebetween through which blanks to be threaded pass, power means for rotating said roller die, a movable feed member carried by said frame for feeding blanks to be threaded into the gap between said roller die and said stationary die, two

movable members having surfaces inclined with respect to each other, means for operatively connecting one of said members to said power means for operatively connecting one of said members to said power means for driving said roller die, means for operatively connecting the other of said members to said feed member, means intermediate said relatively inclined surfaces and engaging the same for causing said members to move in unison, whereby said member connected to said feed member is driven upon movement of the other, moving means for adjustably moving said intermediate means relative to said inclined surfaces to effect displacement between said members, normally inactive adjusting means carried by said frame, and means connecting said adjusting means to said moving means, said last-named means being so constructed and arranged that said moving means may be operative or normally inactive during the thread rolling operation.

5. A thread rolling apparatus comprising a frame, a continuously threaded cylindrical roller die having a plurality of thread starts, means for rotatably supporting said roller die in said frame, a cooperating stationary die having an arcuate concave face having a plurality of thread starts, means for fixedly connecting said stationary die to said frame with said arcuate face disposed adjacent to said roller die with a gap therebetween through which blanks to be threaded pass, power means for rotating said roller die, a movable feed member carried by said frame for feeding blanks to be threaded into the gap between said roller die and said stationary die, two relatively rotatable members having surfaces inclined with respect to each other, means for operatively connecting one of said members to said power means for driving said roller die, means for operatively connecting the other of said members to said feed member, means intermediate said relatively inclined surfaces and engaging the same for causing said members to rotate in unison, whereby one of said members is driven upon rotation of the other, moving means for adjustably moving said intermediate means relative to said inclined surfaces to effect angular displacement between said relatively rotatable members, normally inactive adjusting means carried by said frame, and means connecting said adjusting means to said moving means, said last-named means being so constructed and arranged that said moving means may be operative or normally inactive during the thread rolling operation.
